AUTOMATIC DEVICE FOR OPERATING MACHINE STOPPERS

Filed July 19, 1930

FRANZ PHILIP
By his Attorney
George C. Heinrich

UNITED STATES PATENT OFFICE

FRANZ PHILIP, OF BRONX, NEW YORK

AUTOMATIC DEVICE FOR OPERATING MACHINE STOPPERS

Application filed July 19, 1930. Serial No. 469,233.

This invention relates to improvements in the devices for automatically stopping knitting machines or other thread or yarn using machines as soon as the thread or yarn breaks, 5 slips off its guides or runs out altogether, and it is the principal object of my invention to provide such a device with a stop lever suitably weighted to suit the grade of the yarn which will close a machine stopper circuit 10 upon the breaking, slipping, or running out of the yarn or which will operate in this instance the lever of a mechanical machine stopper.

Another object of my invention is the provision of a housing which is either stationary or rotatably attached to the yarn stand of the machine and in the former case contains a revolving disc provided with stop tongues in its periphery adapted to be arrested by 15 the engagement of the yarn guiding and weighted lever, while in the latter case the disc is stationary and the engagement of the end of the weighted wire will engage the tongues of the disc upon the breaking, slipping, or running out of the yarn to stop the revolution of the housing and to close a circuit for actuating the machine stopper.

It will be clear that with my device I may use any well known type of machine stopper 20 either electrically or mechanically operated; the specific construction of the stopper does not form part of my invention.

A further object of my invention is the provision of a spring controlled guide for the yarn or thread, equipped with means for 25 adjusting the tension of the spring.

A still further object of my invention is the provision of a stationary yarn guide, and a looped end weighted wire normally held in 30 depressed position by the normally running yarn, however, raising under its weight as soon as the yarn breaks, slips, or runs out to operate the circuit closer of an electric machine stopper or the lever of a mechanical machine stopper.

These and other objects and advantages of my device will become more fully known as the description thereof proceeds and will then be specifically defined in the appended 35 claim.

In the accompanying drawings, forming a material part of this disclosure:

Fig. 1 is a top plan view of a thread controlled automatic machine stopper operating device constructed according to my invention, part of the cover being broken away to disclose the interior construction. 55

Fig. 2 is a section on line 2-2 of Figure 1.

Fig. 3 is a cross-section on line 3-3 of Figure 1. 60

Fig. 4 is a fragmentary perspective view of the thread controlled element for operating the machine stopper, during its normal operation.

Fig. 5 is a view similar to Figure 4 illustrating the thread controlled element in operating position to actuate the machine stopper upon breaking, slipping off, or running out of the thread. 65

As illustrated, a housing 10 which may be either stationary or rotating, forms part of the yarn stand on the machine. If the housing 10 is revolving, it turns with its bushing 11 on a ball bearing 12 about a stationary spindle 13, which carries within the housing a disc 14 with a plurality of peripheral stop tongues 15. 70

In this instance an electric cable 16 attached to the stationary arm 13 leads to the switch controlling an electric stopper of the machine of any well known construction, not forming part of this invention, for closing the stopper circuit as soon as the yarn breaks as the housing is grounded in the machine frame, and the stopper element engages beneath the tongues 15. This stopper element is operated by the yarn 18 when broken, slipping off its guides or running out. 80

The stopping element is constructed as follows: Yarn 18 is guided over a guide 19 at the outer end of a wire 20 passed into the interior of the casing 10 where its end is formed into a loop 21 to which one end of a spring 22 is attached; the other end of which is attached to a hook 23 at the end 90 of a screw bolt 24 carrying a nut 25 to allow an adjustment of spring tension. 95

A stationary yarn guide bracket 26 guides the yarn between its lower fingers 27, and a wire 28 has one of its ends formed into a 100

yarn guide 29, while its other end is looped, as at 30, and carries at the apex of the loop a weight 31. The inner end of the looped wire is passed into the housing 10 and while 5 its end 31' remains during the normal operation of the machine above the tongues 15 and disc 14, if however, the yarn breaks, slips off its guides or runs out altogether the lever end will catch under the tongues 15, and will 10 either rotate the disc or stop its rotation to operate a mechanical or electrically operated machine stopper as will hereafter be more fully described.

The housing 10 is attached to the yarn 15 stand and is normally turning therewith in its bushing 11, while disc 14 is stationary, as soon as the yarn breaks, the wire which has been held out of engagement with the disc by the yarn tension, drops and its end 31' enga- 20 gages beneath one of the tongues 15 of disc 14 and rotates the same as well as its spindle 13 which is connected with a movable member of the mechanical stopper (not shown as it forms no part of my invention, any form 25 of mechanical stopper may be used) and operates the same to stop the knitting machine. Or, if an electric stopper is used, the movement of spindle 13 will close the stopper operating circuit. On the other hand if the 30 yarn stand is stationary, and the disc is rotating with any rotary part of the machine, the dropping of the wire upon the breaking of the yarn will engage its end 31' with the tongues 15 and the stopping of spindle 13 35 will operate the mechanical stopper of the machine or close a circuit operating said stopper as above described.

The operation of my device will be entirely clear from the above description and 40 by simultaneously inspecting the drawings, and it will be evident that as soon as the yarn breaks, slips off its guides, or runs entirely out, the lever 30 normally held down by the tension of the thread or yarn, under the influence of its weight will rise at the yarn guiding end while its end 31' normally kept 45 above disc 14 will go down and engage beneath one or the other of tongues 15 to either arrest the rotation of the disc 14, or if the same is stationary rotate the same, and in 50 either case operate the mechanical stopper or close the stopper circuit, if an electrically operated stopper is used, as above described.

It will be understood that I have described 55 and shown the preferred form of my device only as one example of the many possible ways to practically construct the same, and that I may make such changes in its general arrangement and in the construction of its 60 minor details as come within the scope of the appended claim without departure from my invention and the principles involved.

Having thus described my invention what I claim as new and desire to secure by Letters Patent is:

In a device of the class described a spring controlled movable yarn guide, a stationary yarn guide, and a wire loop having its outer end formed into a hook for guiding the yarn, a weight at the apex of said loop normally balanced by the tension of the thread, a stopper tongued disc, a housing therefor, the inner end of said loop extending into said housing and to be kept above said disc during the normal operation of the machine for 75 engaging said stop tongues upon the breaking of the yarn, under the influence of said weight.

Signed at New York, in the county of New York, and State of New York, this fifteenth 80 day of July, A. D. 1930.

FRANZ PHILIP.
